COMBINED CALENDAR AND THERMOMETER

Samuel Tylon, Cleveland, Ohio

Application July 26, 1954, Serial No. 31,614

Term of patent 14 years

(Cl. D74—5)

To all whom it may concern:

Be it known that I, Samuel Tylon, a citizen of the United States of America, residing at Cleveland, in the county of Cuyahoga and State of Ohio, have invented a new, original, and ornamental Design for a Combined Calendar and Thermometer, of which the following is a specification, reference being had to the accompanying drawing, forming a part thereof.

In the drawing:

Figure 1 is a front elevational view of a combined calendar and thermometer showing my new design.

Figure 2 is a side elevational view thereof as it appears in supported position; and

Figure 3 is a rear elevational view of the combined calendar and thermometer as shown in Figure 1.

I claim:

The ornamental design for a combined calendar and thermometer, as shown.
